GROVER LAUBE, OF LONG BEACH, CALIFORNIA, ASSIGNOR TO GEORGE M. WINSTEAD,
OF LONG BEACH, CALIFORNIA.

PHOTOGRAPHIC-PRINTING MACHINE.

Application filed June 18, 1923. Serial No. 646,003.

This invention relates to printing machines, and particularly to photographic printing machines adapted to be used in conjunction with ordinary lamp house cabinets.

In the use of present photographic printing machines, it is not possible to hold the sensitized printing paper in perfect contact with, or with uniform pressure against the film or glass negatives, because film negatives are usually slightly wrinkled, curled or wavy, and furthermore, glass photographic negatives are sometimes of uneven thickness or even wedge-shaped.

15 The main object of the invention is to provide a printing machine comprising means for applying the platen or pressure-back to the sensitized paper against the negative with uniform pressure throughout 20 the entire area thereof, whereby the photographic impression on the sensitized paper will be clear and of uniform tone throughout its entire area.

Another object is to provide a printing 25 machine including a sectional platen or pressure-back and means for first applying one section to a portion of the sensitized paper to hold the same against the negative for a sufficient time to enable the operator 30 to remove his hands from under the platen or pressure-back before the other section thereof is applied to the remaining portion of the sensitized paper.

A still further object is to provide a 35 platen pressure means which can be readily adjusted to vary the pressure of the platen against the negative and printing paper.

A further object is to provide a switching 40 mechanism connected to the lighting circuit, whereby a plurality of exposures can be made of the same duration of time.

Another object is to provide a printing 45 machine including means whereby the electric printing light may be automatically intermittently switched on or off on a printing operation.

A still further object is to provide means for automatically numbering each picture printed on the machine.

50 The above and other incidental objects of a similar nature, which will be hereinafter more specifically treated, are accomplished by such means as illustrated in the accompanying drawings, described in the follow-

ing specification, and then particularly 55 pointed out in the claims which are appended hereto and form a part of this application.

Fig. 1 is a plan view of the machine.

Fig. 2 is a vertical longitudinal section 60 of the machine taken on line 2—2 of Fig. 1 with the platen in printing position.

Fig. 3 is a view similar to Fig. 2 with one section of the platen in printing position and the other section of said platen raised 65 above the sensitized paper.

Fig. 4 is a view similar to Fig. 2 with the platen entirely raised above the sensitized paper.

Fig. 5 is a fragmentary sectional view 70 taken on line 5—5 of Fig. 1 illustrating the numbering device.

Fig. 6 is a bottom plan view of the light switch.

Referring in detail to the drawings, 1 75 (see Fig. 3) indicates a base plate which may be mounted at an angle of substantially 45° on a lamp house cabinet 2. Said plate is provided with a light opening 3 and with a rabbet 4 at the upper edge of said opening to receive the edges of a photographic glass negative 5, or a glass plate and hold the same over said opening with its upper surface flush with the upper surface of the base plate. A platen 6 is hinged above its upper edge to the base plate 1 above the opening 3 by hinges 7, and is preferably formed in two sections, an upper section 8, and a lower section 9, hinged together at their adjoining edges by hinges 10, the upper section being about one-half the length of the lower section. Hinges 7 (see Fig. 1) each comprise hinge members 11 and 12, and a hinge fulcrum rod 13 which extends through knuckles 14 and 15 on said members respectively, the knuckles 14 having vertical slots 16 to receive the ends of said rods to provide for adjustment of the position of the platen up or down with relation to the base plate 1, to accommodate negatives of varying thicknesses.

Hinges 10 comprise each two hinge members, a hinge member 12 above described, a hinge member 17 which is secured to the top of the platen section 9, and a fulcrum rod 18 extending through knuckles 19 and 20 on said hinge members respectively. Around the rod 18 is coiled a spring 21 the

ends of which engage the hinge members 17 and tend to swing the platen section 9 upwardly with relation to the section 8.

On the under sides of plate sections 8 and 9 are secured felt sheets 22 and 23 respectively, which contact with the sensitized paper during a printing operation. A plate 25 is secured to the upper face of base plate 1 adjacent the upper edge of platen 6, carrying bearings 26 and 27 at the lower and upper ends respectively. Coil springs 28 are disposed on the fulcrum rod 13, one end of each of the springs extending under the hinge member 12 of hinges 7, while the other ends thereof engage the under side of pins 29 projecting from bearing members 26, the springs normally maintaining the sectional platen 6 out of contact with the base plate 1 of the apparatus.

A bar 30 is longitudinally and centrally secured to the upper side of the platen section 9 and is provided on its lower end with an upturned lip 31 that engages the end of a track bar 32 to limit the upward movement of the platen when it is released after a printing operation. One end 33 of track bar 32 is pivotally mounted in a bearing 34 secured to the upper side and edge of platen section 8 and extends longitudinally of the platen above the bar 30 not quite to the lower edge of section 9 and carries in its lower end a set screw 35 for adjusting the pressure on the platen. Journaled in bearing members 26 are a pair of V-shaped bearing rollers 36, disposed one above the other, bearing members 27 also carrying a pair of similarly disposed rollers 37, a pressure rod 40 being reciprocatingly mounted between the pairs of bearing rollers 36 and 37. Pressure rod 40 extends over the track bar 32 and carries on its free end a contact roller 41 that engages the track bar as clearly shown in Figs. 1 and 2 of the drawings.

A rock shaft 42 extends transversely of base plate 1 and is journaled in bearing members 26 and in bearings 43 and 44 secured to the base plate. Rigidly mounted on rock shaft 42 between bearing members 26 is an arm 45, its free end being pivotally connected to the upper end of pressure rod 40, whereby the rod will be reciprocated on a rocking motion of the shaft 42. An operating handle 47 is rigidly secured on the shaft 42 between the bearings 43 and 44 for operating the apparatus, as will be more particularly set forth.

A numbering stamp 50 (see Figures 1, 2 and 5) of usual construction is pivotally mounted at 51 in a bracket 52 secured to the upper corner of the platen section 8, the upper edge of the section being notched as at 53 to accommodate the imprinting end of the stamp when the platen is brought against the sensitized paper on the negative for imprinting a number on the photograph-

ic print. A plate 54 is secured to the top of the numbering stamp 50 which is engaged by an arm 55, mounted on an arm 56 projecting from and secured to one of the bearing members 26 when the platen 6 is raised, whereby when the stamp is swung on its pivot and the type 57 of the stamp, is brought into printing position it will wipe an inking roller 58 secured on a shaft 59 journaled at its ends in hinge members 12, thus inking the type so that they will number the picture when the platen is swung down against the sensitized paper on the negative.

An electric switch 60 is mounted on the under side of the base plate 1 for controlling an electric lamp 61, located within the lamp box housing 2, the switch including a contact plate 62, switch arm 63 adapted to wipe the plate, and a spring 64 connected to one end of arm 63 for normally holding the contact end of the arm out of contact with the contact plate and breaking the lamp circuit. The lamp circuit includes a battery 65, line 66 connected to one pole of said battery and to the contact plate 62, a line 67 is connected to the other pole of the battery terminal of said lamp and to the contact arm 63. A switch closing lever 70 is pivoted in a bearing 71 on the base plate and extends through a slot 72 in the plate for engaging the switch arm 63, there being a block 73 of insulation in said arm with which said lever 70 contacts to prevent short circuiting. An arm 75 is secured on the rock shaft 42 for engaging the upper end of lever 70 so that the lever will engage switch arm 63 and close the switch 60 and light the lamp 61 when the shaft 42 is turned by the handle 47 to swing the platen 6 against the sensitized paper as illustrated in Fig. 2.

The operation of my invention is as follows. The platen 6 being raised, as shown in Fig. 4 of the drawings, a negative 5 is placed in the rabbets 4 over the opening 3 and a sheet 80 of sensitized paper placed upon said negative, which sheet is first held in position on said negative by the operator's left hand. The operator then grasps the handle 47 and swings the same downwardly toward the base plate 1, which correspondingly turns the shaft 42 and the arm 45. The arm 45 through the link 46 draws the pressure rod 40 downwardly, whereupon the pressure rod roller 41, engaging the track bar 32 at its upper end, travels downwardly over said bar and swings the platen 6 downwardly against the tension of spring 28 until the upper section 8 thereof first engages the upper portion of the sensitized paper 80 and clamps said portion against the upper portion of the negative 5. The sensitized sheet being thus clamped against the negative, the operator removes his left hand from said sheet and continues with his right hand to

swing down the handle 47, which through the medium of shaft 42, arm 45, and link 46, causes the rod 40 to travel downwardly and the roller 41 to travel correspondingly 5 down the track bar 32, whereby the platen section 9 through said bar and the set screw 35 in contact with bar 30 is caused to swing down against the tension of spring 18, against the remaining lower portion of the 10 sheet 80 and clamp said portion of the sheet firmly against the remaining portion of the negative 5. The pressure rod 40 is so positioned by the rollers 36 and 37, and the set screw 35 so adjusted that the engagement of 15 the pressure rod roller 41 with the bar 32 through said set screw and bar 30, causes both sections 8 and 9 of the platen to clamp the sheet 80 with uniform pressure against the negative 5 throughout the entire area of 20 said sheet and negative. By adjusting the set screw 35, the track bar 32 may be adjusted on its pivot with relation to the pressure bar roller 41 to vary the pressure of the platen.

25 As the platen section 8 is swung down against the sheet 80, the stamp plate 54 is disengaged from plate 55, whereupon the stamp 50 that is inked by roller 58 swings by gravity on its pivots 51 until its impression end enters the recess 53 in the upper edge of said platen section, the type on the impression end of the stamp contacting with the back of the sheet 80 at one upper corner thereof and impresses the number of the 30 print on said sheet as clearly illustrated in Fig. 5. The numbering wheels of the stamp are changed each time by hand before the next print is made so that the stamp will number each sheet properly.

35 When the platen is swung down each time and the sheet 80 clamped thereby against the negative 5, the arm 75 engages and swings the lever 70 on its pivot 71, whereupon said lever, engaging switch arm 63, 40 swings said arm upon contact 62 and closes the switch 60 and the lamp circuit, thus lighting the printing lamp 61 so that the light thereof, projecting through opening 3 and the negative 5, will print the negative on the sensitized sheet 80 until the platen is raised. Upon raising the platen the arm 75 disengages the lever 70 and the spring 64 swings the switch arm 63 out of contact with contact 62, thus opening the switch 60 and the lamp circuit and putting out the lamp 61 and ending the printing of the picture.

45 What I claim is—

1. In a printing machine, a base plate provided with a light opening and means for holding a negative over said opening, a sectional platen, means for swinging said platen against the sensitized sheet upon said negative, means acting against the platen, for exerting and equally distributing a uni-

form pressure on said platen, whereby the sensitized paper will be held in uniform engagement with the negative throughout its entire area and an adjusting screw engaging one of the platen sections for varying 70 the pressure against said platen.

2. In a printing machine, a base plate provided with a light opening, a platen formed in two sections hinged together, one of said sections being hinged to said base plate, means for normally swinging said sections away from said plate, means for normally swinging said sections out of clamping alignment with each other, a track bar pivoted to one of said sections and extending over the other section, a pressure bar reciprocatively mounted on said base plate, and means for reciprocating said pressure bar so that said bar will contact with and travel over said track bar in one direction to swing said platen sections successively into clamping position with uniform pressure against the sensitized sheet upon said negative.

3. In a printing machine, a base plate provided with a light opening, a platen formed in two sections hinged together, one of said sections being hinged to said base plate, means for normally swinging said sections away from said plate, means for normally swinging said sections out of clamping alignment with each other, a track bar pivoted at one end to one of said sections and extending over said sections, a set screw mounted in the free end of said track bar engaging 90 said other section, a pressure bar reciprocatively mounted on said base plate, and means for reciprocating said pressure bar so that said bar will contact with and travel over said track bar in one direction to swing said platen sections successively into clamping position with uniform pressure against the sensitized sheet upon said negative.

4. In a printing machine, a base plate provided with a light opening, a platen for clamping a sheet of sensitized paper on said negative, hinges for securing said platen to said base plate, one member of said hinges being secured to said base plate and provided with upwardly extending slots, the other member of said hinges being secured to said platen and formed with knuckles, the fulcrum pin of said hinges extending through said knuckles and said slots, whereby the platen may adjust itself with relation to the base plate to accommodate negatives of varying thickness thereunder, and means for swinging said platen toward said base plate to clamp a sheet of sensitized paper upon said negative.

5. In witness that I claim the foregoing I have hereunto subscribed my name this 26th day of May, 1923.

GROVER LAUBE.
